RING GAUGE

Howard D. Solomon, Chicago, Ill., assignor to
Lou-Edna Solomon Trusts

Filed Dec. 30, 1959, Ser. No. 58,855

Term of patent 14 years

(Cl. D52—6)

Fig. 1 is a top plan view of the face of a ring gauge embodying my new design;

Fig. 2 is a plan view of the back; and

Fig. 3 is an edge view of the same.

I claim:

The ornamental design for a ring gauge, substantially as shown.
